UNITED STATES PATENT OFFICE.

JOHN F. McCARTHY, OF SALTSBURG, PENNSYLVANIA.

OVERSHOE-FASTENER.

SPECIFICATION forming part of Letters Patent No. 642,705, dated February 6, 1900.

Application filed March 1, 1899. Serial No. 707,338. (No model.)

To all whom it may concern:

Be it known that I, JOHN F. McCARTHY, a citizen of the United States of America, residing at Saltsburg, in the county of Indiana and State of Pennsylvania, have invented certain new and useful Improvements in Overshoe-Fasteners, of which the following is a specification, reference being had therein to the accompanying drawings.

10 My invention relates to certain new and useful improvements in overshoe-fasteners. The object of my invention is to provide a simple and efficient means for keeping an overshoe from slipping; and it consists of an 15 elastic cord or band which is adjustable and provided with a suitable connecting device for attaching to the overshoe, in combination with a fastening-plate, to which the band or cord is secured for connecting the same to 20 a shoe.

My invention finally consists in the novel combination and arrangement of parts hereinafter more fully described, and particularly pointed out in the claim hereunto appended.

25 In describing the invention in detail reference is had to the accompanying drawings, forming a part of this specification, wherein like numerals of reference indicate corresponding parts throughout the several views 30 thereof, and in which—

Figure 1 is a perspective view of a portion of a shoe and overshoe, showing my improved fastener in position. Fig. 2 is a vertical sectional view thereof. Fig. 3 is an inverted 35 perspective view of the fastening-plate. Fig. 4 is a perspective view of the connecting-plate. Fig. 5 is a perspective view of a modified form of connecting-plate attached to a portion of an overshoe, and also showing a 40 portion of the adjustable elastic cord or band connected thereto. Fig. 6 is a perspective view of a modified form of connecting-plate, showing the aperture in one bend thereof, through which is inserted the fastening-barb.

45 Referring to the drawings by reference-numerals, 1 indicates the shoe, and 2 the overshoe, which are both broken away, as shown. The overshoe is secured to the shoe to prevent the slipping off of the same by means of 50 the connecting-plate 3, which is provided with the oblong slot 4. The connecting-plate 3 is also provided with a pair of barbs 5 on

its inner face, which are adapted to be inserted in the overshoe, as shown, for securing the plate thereto.

55 Suitably connected to the plate 3, in any desirable manner, is the adjustable elastic cord or band 6, the lower end thereof being inserted through the slot 4, lapped upon itself, and secured together in any desirable manner.

60 The upper end of the cord or band 6 is connected to the fastening-plate 7. This plate 7 is formed of an oblong piece of flat metallic material having a pair of oblong slots 8 65 9 suitably arranged therein and at the lower end is provided with the fastening-barb 10. The outer face of the plate 7 is formed with the eye 11, while the inner face has formed integral therewith the downwardly-extending hook 12.

70 In Fig. 5 of the drawings I have shown a modified form of connecting-plate for the elastic cord or band, and it consists of an oblong plate 13, bent upon itself, the outer face of the inner portion having a flexible 75 projection 14, which operates through an aperture formed in the outer bent portion, as shown, the band or cord being secured to the link 15, which is likewise connected to the connecting-plate.

80 My improved overshoe-fastener is connected to the overshoe, as well as the wearing-shoe, in the following manner: The connecting-plate 3 is secured to the overshoe by means of the barbs 5. It will of course be 85 observed that before the connecting-plate 3 is secured to the overshoe the elastic cord or band is connected thereto. The upper or free end of the cord or band is inserted through the aperture or slot 9 in the fastening-plate 7, then passes downwardly over the outer face of the plate 7, and thence through the slot 8. Then it is passed downwardly and around the plate and secured in position 90 by means of the barb 10. The free end of 95 the cord or band is then inserted in the eye 11. The plate is then supported by means of the hook 12, which is attached to the upper edge of the shoe-upper.

100 The modified form of connecting-plate is secured to the overshoe by means of the flexible barb operating through the same and through the aperture formed in the outer portion of the plate. The barb is then bent

downwardly, which will securely hold the plate in position.

It will of course be observed that by the use of the fastening-plate the cord or band 5 can be adjusted to any length desired.

It will be noted that various changes may be made in the details of construction without departing from the general spirit of my invention.

Having thus fully described my invention, what I claim as new, and desire to secure by Letters Patent, is—

An overshoe-fastener consisting of an elastic cord or band, a fastening-plate provided 15 with a pair of oblong slots one above the other adapted to receive the upper end of the said band, a barb formed integral with the lower edge of the said fastening-plate for securing

the said cord or band in position, a hook suitably connected to the said fastening-plate adapted to engage the upper edge of a shoe for supporting the said plate and cord or band, means formed integral with the said plate at the top of one side thereof for retaining the free end of said band, and a connecting-plate connected to the lower end of the said cord or band and secured to an overshoe for securing the same in position, substantially as described.

In testimony whereof I affix my signature 30 in the presence of two witnesses.

JOHN F. McCARTHY.

Witnesses:

JOHN A. KAIB,
JOHN S. IRWIN.
